UNITED STATES PATENT OFFICE

2,007,815

ROLLING MILL

Barton R. Shover, Pittsburgh, Pa.

Application April 22, 1932, Serial No. 606,842

9 Claims. (Cl. 80—34)

My invention relates to rolling mills and, in particular, to a so-called universal mill, the mounting of the vertical rolls therein, and the drive therefor, although additional features of novelty are also contemplated.

In universal mills, as previously constructed, the horizontal and vertical rolls have generally been driven from the same pinion stand. In such installations, any change in the size of the horizontal rolls necessitates a change in the size of the vertical rolls in order to maintain the peripheral speeds of both sets of rolls identical. In a comparatively few installations, each pair of vertical rolls has been driven by an individual motor. While this arrangement relieves the necessity for changing the vertical rolls when changing the horizontal rolls, since the speed of the vertical rolls may be adjusted independently of that of the horizontal rolls, it is still necessary that both vertical rolls be of the same diameter.

In all present types of universal mills with which I am familiar, the vertical rolls are driven by a square horizontal shaft or round shaft with splines having driving bevel pinions slidable thereon meshing with gears on the vertical roll shafts. The sliding bevel pinions and their bearings take up considerable space on the drive shaft and if smaller widths of material are to be rolled, the pinions must be disposed on the housing sides of the axes of the vertical rolls. This arrangement limits the maximum width which the mill can roll to the spacing between housings, less the total length of the bevel pinions and their bearings along the drive shaft. If maximum widths are to be rolled, driving pinions may be placed on the pass side of the vertical rolls but this arrangement correspondingly limits the minimum width for which the vertical rolls can be adjusted.

The present arrangement of the drive for the vertical rolls, as above described, renders it very difficult to change these rolls and considerable operating time is thus lost whenever changes or repairs become necessary.

It is desirable in universal mills to have the vertical rolls as close as possible to the horizontal rolls. This arrangement has usually been unattended by any difficulties heretofore. The desirability of using anti-friction bearings for the mill rolls, however, introduces some complications. Since present anti-friction bearings of capacities sufficient to withstand the rolling pressures must be of greater diameter than the roll itself, a greater clearance between the vertical and horizontal rolls is necessary when anti-friction bearings are used than when present types of bearings are employed, because in changing rolls, the bearing housing must pass the vertical rolls.

Even with the fairly close clearance between

vertical and horizontal rolls which is possible with present types of bearings, it is sometimes desired to roll a slab shorter than the distance between the center line of the vertical rolls and the bite of the horizontal rolls so that the vertical rolls cannot deliver the slab to the horizontal rolls.

I have invented a rolling mill which overcomes the foregoing objections to mills of known types. In accordance with my invention, I provide a separate driving motor for each of the vertical rolls. Each roll is independently removable from the mill without disturbing the other so that repairs or replacements can be effected within a very short time. It is not necessary, furthermore, that the vertical rolls both be of the same diameter or of a fixed diameter relative to that of the horizontal rolls.

The invention also contemplates means permitting the removal of horizontal rolls equipped with anti-friction bearings without disturbing the vertical rolls. A close clearance between vertical and horizontal rolls is also permitted. A driven auxiliary supporting roll, furthermore, is incorporated in the mill between the vertical and horizontal rolls to deliver slabs shorter than the distance between said sets of rolls.

For a complete understanding of the invention, reference is made to the accompanying drawings illustrating a present preferred embodiment of the invention. In the drawings:

Figure 1 is a side elevation of the mill showing a portion thereof in section;

Figure 2 is a view partly in plan and partly in section along the line II—II of Figure 1, certain portions being broken away for clearness;

Figure 3 is an end elevation of the mill; and

Figure 4 is a sectional view along the line IV—IV of Figure 2.

Referring now in detail to the drawings, a rolling mill according to my invention comprises housings 10 and 11 supported on shoe plates 12. Windows 13 in the housing are enlarged adjacent the bottom thereof to receive roller bearings 14. The roller bearings 14 are supported in yokes 15 bolted to the housing at the edge of the lower portion of the window. Keepers 16 bolted across the yokes 15 maintain the roller bearings in their supporting yokes. The mill has a bottom roll 17 having necks 18. The necks 18 rest on the roller bearings 14 to support the bottom roll in the housing. This type of bearing for supporting the bottom roll is described more fully and claimed in my prior Patent No. 1,931,078, granted November 20, 1934, for Rolling mills. End rings 19 bolted across the window 13 co-axially with the bottom roll prevent lateral movement thereof. The main mill drive is not part of this invention and is, therefore, not shown.

The mill also has a top roll 20. The top roll

has necks 21 which are journaled in any suitable type of bearing carried in bearing housings 22. The bearing housings 22 are slideable vertically in the windows 13 guided by rails 23 bolted to the edge of the window. One side of each housing window is provided with a removable angle liner plate 23a for a purpose which will presently appear. The housing windows are recessed at 23b to receive the long leg of the plate 23a on partial removal thereof. The bearing housings 22 and the top roll 20 carried thereby are normally maintained in position by a suspension including beams 24 extending across the mill and secured to the bearing boxes by pins 25. A clevis 26 is pinned to each of the beams 24. The clevises are secured to a crosshead 27 carried by a hydraulic cylinder 28 reciprocating on a fixed piston 29. The piston 29 is supported on a transom 30 extending between the housings 10 and 11. Suitable fluid pressure maintained within the cylinder 28 holds the top roll of the mill in adjusted position. This apparatus is described more fully and claimed in my prior Patent No. 1,948,804, granted February 27, 1934, for Screwdowns.

The position of the bearing housings 22 and, therefore, that of the top roll 20, is determined by the setting of the main screwdowns indicated at 31. Thrust bearings 32 are provided between the ends of the screwdowns and the bearing housings 22. Worm wheels 33 mounted in housings 34 have a sliding fit by means of splines or squared portions with the screwdowns 31. Worms 35 on worm shafts 36 mesh with the worm wheels 33. The shafts 36 are journaled in housings 37. Gears 38 on the shafts 36 are driven by pinions 39 on pinion shafts 40. The shafts 40 are journaled in housings 41 and are driven by a main screwdown motor 42 through couplings 43. The motor 42 is mounted on a top transom 44 extending across the mill.

The motor 42 may be controlled manually or automatically to provide the desired setting between the horizontal rolls 17 and 20. The screwdown drive includes a spur gear reduction and a worm gear reduction so that a very fine control of the screwdown movement is afforded.

On the entering side of the mill (the left-hand side in Figures 3 and 4), guide rails 45 and 46 extend across the mill and are suitably secured at their ends to the housings 10 and 11. Housings 47 and 48 are carried on the rails 45 and 46. The lower ends of the housings 47 and 48 are bifurcated and provided with bearing strips 49 engaging the sides of the rail 46. Rollers 50 are journaled in the bifurcated lower ends of the housings on shafts 51 and engage the top face of the rail 46 to facilitate movement of the housings axially of the mill rolls. Yokes 52 surround the rail 45 and are bolted to the housings 47 and 48. Bearing strips 53 on the yokes 52 and the housings 47 and 48 engage the side faces of the rail 45. The housings 47 and 48 are thus rigidly supported but are adapted for transverse adjusting movement.

Vertical rolls 54 having integral shafts 55 are journaled in the housings 47 and 48. Gears 56 are mounted on the upper ends of the shafts 55. Pinions 57 meshing with the gears 56 are keyed to intermediate shafts 58 journaled in the housings 47 and 48. Worm wheels 59 keyed to the shafts 58 are contained in housings 60 mounted on the housings 47 and 48. The housings 60 are also provided with shafts 61 having worms 62 meshing with the worm wheels 59. Motors 63, supported in any suitable manner, are provided with ex-

tensible couplings 64 through which they drive the shafts 61.

Each vertical roll is thus provided with an independent drive comprising a motor 63, the worm reduction gears 59, 62, and the spur reduction gears 56 and 57. The drive for the rolls also includes the extensible couplings 64, so that transverse adjustment of the vertical rolls for different widths is permitted even though the motors 63 are mounted on a stationary foundation. The ribs of housings 10 and 11 are offset at 65 to provide clearance for the outer ends of the gear housings 60 when the vertical roll housings 47 and 48 are retracted to their extreme outermost position, as shown in Figure 1.

The vertical roll housings are urged toward their outermost position by counterweights or hydraulic retracting means (not shown) similar to that shown for the top roll 20. The housings 47 and 48 may be adjusted inwardly by vertical roll screwdowns 66. Each screwdown 66 comprises a pair of screws 67 traversing nuts 68 seated in the housings 10 and 11. Thrust bearings 69 are provided between the ends of the screws and the housings 47 and 48. The ends of the screws 67 are squared as at 70 and gears 71 are slidably mounted on such squared ends. The gears 71 are enclosed within housings 72 bolted to the main housings 10 and 11 and are driven by pinions 73 therein keyed to shafts 74. The shafts 74 are driven by motors 75 through speed reducing gears 76.

A transom 77 extends across the mill on the entrance side thereof and is bolted at its ends to the housings 10 and 11. The transverse portion 35 of the transom is omitted in Figures 1 and 2 for the sake of clearness but the bolt holes for securing it to the housings are shown in Figure 1. The transom 77 is provided with a bearing arm 78 projecting therefrom between the vertical rolls 40 and toward the bite of the horizontal rolls. An auxiliary supporting roll 79 is journaled in the arm 78. A driving roll 80 is also carried by the arm 78. The roll 80 engages the roll 17 and the roll 79 for frictionally driving the latter from the former. If desired, the roll 80 may be provided with spring-pressed bearings for maintaining it constantly in engagement with the rolls 17 and 79.

The function of the roll 79, of course, is to make it possible to handle slabs shorter than the horizontal distance between center lines of the vertical and horizontal rolls. The slab is normally fed to the mill by a front roll table (not shown) and, if desired, idling rolls may be carried by the arm 78 between the end of the front table and the intermediate driven roll 79. Instead of using the extensible couplings 64 in connection with stationary driving motors 63, the armature shaft of the driving motor may be coupled to shaft 61 and the motor 63 moved with the housings 47 and 48.

The operation of the mill described above is substantially the same as that of present types of universal mills. The construction described, however, is characterized by several important advantages over previous mills. In the first place, since the vertical rolls each have their own driving motor, and are thereby independent of each other and the horizontal roll drive, the flexibility of the mill is greatly increased because it is not necessary to make the diameter of the vertical rolls equal, or to maintain any fixed relation between the diameters of the vertical and horizontal rolls. Regardless of differences of the diameter of the vertical rolls or their relation to the 75

5 diameters of the horizontal rolls, the desired peripheral roll speed can be maintained by adjusting the speed of the separate motors for driving the vertical rolls. The arrangement provides for a greater range between maximum and minimum rolling widths for a given distance between the main roll housings than has been obtainable heretofore. The limitations on vertical roll adjustment which are imposed by the previous 10 drives for the vertical rolls have been entirely overcome.

Another advantage of the mill is that the vertical rolls may be removed independently with little difficulty. It is necessary only to disconnect 15 the coupling between the motor and the vertical roll, and then remove the yoke holding the vertical roll housing against its upper guide rail. The entire vertical roll housing may then be lifted vertically from the mill and replaced by 20 a similar unit in a very short time so that failure of either vertical roll or its drive does not necessitate halting mill operation very long.

The mill is adapted for anti-friction bearings 25 for the main rolls, in accordance with the present trend in mill design. The spacing of the vertical and horizontal rolls, furthermore, need not be made excessive to provide clearance for the bearing housings. When it is desired to change the horizontal rolls, partial removal of the plates 33a 30 so that their longer legs lie in the recesses 33b in the housings, provides the necessary clearance to permit the anti-friction bearings for the main rolls to pass by the vertical rolls.

The provision of an auxiliary driven roll between the vertical and horizontal rolls makes it 35 possible to roll slabs having a length less than the spacing between the vertical and horizontal rolls.

Although I have illustrated and described herein but a single present preferred embodiment of the invention, it will be recognized that many changes therein may be made without departing from the spirit thereof or the scope of the appended claims.

45 I claim:

1. In a rolling mill, the combination with a 50 pair of housings, windows in the housings, bearings mounted therein and a horizontal roll supported in said bearings, of a vertical roll, means for supporting it adjacent the horizontal roll so that it precludes axial movement of the horizontal roll and its bearings relative to the housings, and a removable liner in said window permitting lateral movement of the horizontal roll 55 and its bearings to clear the vertical roll and its support.

2. In a rolling mill, a pair of housings, a horizontal roll supported on bearings in said housings, a vertical roll and bearings therefor positioned adjacent the horizontal roll so as to interfere with axial movement thereof with its bearings, and removable means supporting the horizontal roll bearings against lateral movement in the housings to clear the vertical roll and its 60 bearings.

3. In a rolling mill, a horizontal roll and bearings therefor mounted in housings but removable therefrom for roll changes, a vertical roll supported close to the horizontal roll so as to prevent axial movement of the latter with its bearings in the housings, and means whereby the horizontal roll and its bearings may be moved laterally in the housings to clear the vertical roll.

4. In a rolling mill, the combination with a pair of main housings, and transverse rails extending therebetween, of vertical roll housings mounted on said rails for adjustment laterally of the mill, the bottoms of said vertical roll housings being slotted to receive one rail, and the upper ends of the vertical roll housings being releasably attached to the other rail, a worm and worm wheel drive in each of said vertical roll housings, an individual motor for operating each 10 of said drives, extensible couplings between the motors and the drives, said drives being offset from the axes of the vertical roll housings along the path of material traversing the mill, whereby the vertical roll housings may be retracted into 15 engagement with the main housings.

5. In a rolling mill, the combination with a pair of main housings, and transverse rails extending therebetween, of vertical roll housings mounted on said rails for adjustment laterally 20 of the mill, the bottoms of said vertical roll housings being slotted to receive one rail, and the upper ends of the vertical roll housings being releasably attached to the other rail, a worm and worm wheel drive in each of said vertical roll housings, an individual motor for operating each 25 of said drives, extensible couplings between the motors and the drives, said drives being offset from the axes of the vertical roll housings along the path of material traversing the mill, whereby the vertical roll housings may be retracted into 30 engagement with the main housings, said main housings being offset adjacent said drives to permit further retraction of the vertical roll housings.

6. In a universal mill, a pair of housings, horizontal and vertical rolls rotatably supported in said housings, a transom extending between the housings on the same side of the horizontal rolls as the vertical rolls, a bearing arm projecting 40 between the horizontal rolls from the transom, and a feed roll journaled in said arm between the horizontal and vertical rolls.

7. The apparatus defined by claim 6 characterized by a friction drive between the feed roll and 45 one of the horizontal rolls.

8. In a rolling mill, the combination with a pair of housings, bearings mounted therein, and horizontal rolls journaled in said bearings, of vertical roll housings, rails extending between the first-mentioned housings supporting said vertical roll housings from said first-mentioned housings for transverse movement, working rolls journaled in said vertical roll housings, individual driving motors for said last-mentioned rolls, and extensible couplings connecting the driving motors and the vertical rolls.

9. In a rolling mill, the combination with a pair of housings, bearings mounted therein, and horizontal rolls journaled in said bearings, of vertical roll housings, rails extending between the first-mentioned housings supporting said vertical roll housings from said first-mentioned housings for transverse movement, working rolls journaled in said vertical roll housings, individual driving motors for said last-mentioned rolls, a worm and worm wheel drive in each of said vertical roll housings, and extensible couplings connecting said motors to the worms of said drives.
